Ex
OR D 811

Des. 811

Garrison Smith, Henry Brown & Joseph A. Read, of Philadelphia, Pa.

Assignors to Leibrandt, M. Dowell & Co., of the same place

Letters Patent No. 811. Dated June 24th 1856.

The schedule referred to in these Letters Patent and making part of the same.

To all whom it may concern:

Be it known that we, Garrison Smith, Henry Brown, and Joseph A. Read, all of the City of Philadelphia, and State of Pennsylvania, have invented or produced "a new and original design for a cooking stove," and we do hereby declare, that the accompanying drawing is a clear

and exact representation of the same.

Fig. 1, being a front view of our improved design for cooking stove.

Fig. 2, an end view of the same.

Fig. 3, a ground plan of the lower plate

Fig. 4, a sectional view (full size) of the molding on the edge of the upper plate.

Fig. 5, a sectional view (also full size) of the molding on the edge of the lower plate.

A, is the top plate of the stove. B, the bottom plate. C, the front plate, and D, the end plate.

The top plate A, has a molding a, round its edge of the form shown in Fig. 4.

The bottom plate B, is of the form seen in Fig. 3, and has a molding b, on its edge represented in Fig. 5.

The front plate C, has a molding c, on the top and moldings d, on the bottom, and moldings e, on the edges, and two ornaments f and g, near each edge.

The front plate is also furnished with four doors, h, i, j, & k, each having moldings and ornaments seen in fig. 1.

The end plate D, is also furnished with moldings and ornaments as seen in Fig. 2.

We claim the combination of the various ornaments and moldings on the several plates and doors, as shown in the drawing, the whole forming an ornamental design for a cooking stove.
